attys.

UNITED STATES PATENT OFFICE.

ARCHIBALD B. CLEMENTS, OF NEW YORK, N. Y., ASSIGNOR TO THE LAMSON COMPANY,
OF SYRACUSE, NEW YORK, A CORPORATION OF MASSACHUSETTS.

CASH CARRIER.

Application filed June 27, 1923. Serial No. 648,036.

To all whom it may concern:

Be it known that I, ARCHIBALD B. CLEMENTS, a citizen of the United States of America, and resident of New York, in the county of Bronx and State of New York, have invented new and useful Improvements in Cash Carriers, of which the following is a specification.

This invention pertains to cable cash carrier systems and relates more particularly to improvements in the cash carriers of such systems.

The principal object of the present invention is to provide a carrier having cable gripping elements of an efficient and durable type adapted for use with cables or cords of widely different sizes, mounted wholly within the bottom unit of the carrier and entirely free from direct connection with the cash box proper so as to permit ready substitution or replacement of the latter if desired, and avoiding any curtailment of the space within the box.

In the accompanying drawings a preferred embodiment of the invention is illustrated by way of example and in such drawings:

Fig. 1 is an end elevation of the improved carrier.

Fig. 2 is a side elevation of the carrier.

Fig. 3 is a bottom plan view of the cash box removed from the bottom unit of the carrier.

Fig. 4 is a top plan view of the upper member of the bottom unit.

Fig. 5 is a bottom plan view of the upper member of the bottom unit.

Fig. 6 is a top plan view of the lower member of the bottom unit.

Fig. 7 is a bottom plan view of the lower member of the bottom unit.

Fig. 8 is a vertical section on line 8—8 of Fig. 6, and

Fig. 9 is a vertical section on the line 9—9 of Fig. 6.

Referring to the drawings, the numeral 1 indicates generally the bottom unit of the improved carrier, such bottom unit being of elongate rectangular shape having its corners rounded. This bottom unit comprises the upper member 2 having the outstanding lateral flanges 3. The member 2 is preferably constructed of some non-metallic ma-

terial such, for example, as indurated fibre. The upper member of the bottom unit is 55 furnished with a central cavity 4 whose sides are defined by the walls 5, 6 respectively, preferably integral with the base plate 2.

The under side of the cavity in the member 2 is closed by the lower member 7 of the bottom unit, provided with a slot or opening 8, and secured to the upper member in any desired manner, but preferably as hereinafter described. A pivot pin 9 is secured to the lower member 7 in any desired manner, for example by heading it over against the under surface of said member, the upper end of the pin being received in an opening 9^a in the upper member 2. 70

A cable gripping lever 10 is pivotally supported by the pin 9 to swing in a plane substantially parallel to the plane of the upper member 2. This cable gripping lever is furnished with a downwardly extending arm 11 which passes through the slot or opening 8 in the lower member 7 and which is furnished with the cable gripping face 12. 75

A bracket 13 is arranged within the cavity 4 in the bottom unit, preferably being secured by rivets or screws to the lower member 7, and as here illustrated the upper member 2 has an opening 13^a for the accommodation of the upper part of the bracket. This bracket comprises the spaced ears 14, 15 having openings respectively for the reception of the opposite ends of the pintle pin 16. 80

A second cable gripping jaw 17 is supported by the pintle pin 16 so as to have 90 a hinged connection with the bracket. This jaw 17 is furnished with a cable gripping face 18 which cooperates with the face 12 of the jaw 10. The arrangement of the bracket 13 and the pintle pin 16 is such that the jaw 17 swings about an axis substantially parallel to the plane of the member 2 and to the longitudinal axis of the bottom unit. The jaws 10 and 17 thus swing about axes substantially at right angles to each other. 95

The jaw 17 is furnished with a shoulder 19 having a projection 20 which is opposed to a projection 21 carried by a bridge member 22 connecting the ears 14, 15 of the bracket 13. A coil spring 23 is interposed 105

between the ear 22 and the shoulder 19, being centered by the members 20 and 21. This spring normally tends to swing the jaw 17 toward its operative, cable gripping position.

The jaw 10 is furnished with an arm 24, and a spring 25 bears at one end against this arm, the opposite end of the spring being secured to a fixed element of the bottom unit, preferably to the post 7^b herein-after described. A cash box 26 of usual construction is removably secured to the upper surface of the member 2 in any desired manner, preferably as hereinafter described, so as to permit replacement when necessary.

For securing the several parts in proper relationship, the bottom member is furnished with upstanding sleeve-like, internally screw threaded posts 7^a, 7^b which, when the parts are assembled, project up through openings 2^a, 2^b respectively in the upper member 2 and receive the threaded ends of screws S passing downwardly through openings 1^a, 1^b in the bottom of the cash box 26, the latter openings aligning respectively with the internally threaded posts 7^a, 7^b.

The spring pressed jaws 17 and 10 grip the cable C of the despatch system in the usual manner for connecting the carrier and the cable so that the longitudinal axis of the carrier lies substantially parallel to the axis of the cable, and may be disengaged from the cable by means of the usual cam devices well known in the art.

In accordance with the present invention, both jaws, together with their operating elements, are mounted within and form portions of the bottom unit of the carrier so that they are entirely independent of the cash box. The interior of the latter is thus free from any obstructions and may be made of any suitable shape without regard to the cable gripping devices. At the same time the cash box and bottom unit, being independent, may readily be separated, if desired, for repair or replacement of parts or for the substitution of cash boxes of different size and form, while permitting the bottom unit with its gripping devices to be made of a standard size and pattern.

I claim:

1. A cash carrier for cable despatch systems combining a bottom unit, a box mounted thereon, and a pair of cable gripping elements carried by the bottom unit and ar-

ranged to swing about axes lying respectively in intersecting planes.

2. A cash carrier for cable despatch systems comprising a bottom unit, a box carried thereby, a cable gripping element hinged to the bottom unit to swing about an axis substantially parallel to the plane of the box engaging face of the bottom unit, and a second cable gripping element pivoted to the bottom unit to swing about an axis substantially perpendicular to the axis about which the first named gripping element swings.

3. A cash carrier for cable despatch systems having a bottom unit, a box secured to the bottom unit, a cable gripping jaw hinged to the bottom unit to swing about an axis substantially parallel with the axis of the cable with which the box cooperates, and a second cable gripping jaw movably secured to the bottom unit of the carrier.

4. A cash carrier for cable despatch systems comprising a bottom unit having a cavity therein, a bracket secured in the cavity, said bracket having a pair of spaced ears, a pivot pin extending between said ears, a cable gripping jaw supported by the pin, a spring bearing against said jaw and abutting a part of the bracket, and a co-operating cable gripping jaw also carried by the bottom unit.

5. A cash carrier for cable despatch systems comprising an elongate bottom unit having a box mounted thereon, a bracket secured to the bottom unit, a spring pressed cable gripping jaw carried by the bracket and arranged to swing about an axis substantially parallel to the longitudinal axis of the bottom unit, and a second gripping jaw pivotally supported by the bottom unit to swing about an axis substantially perpendicular to the longitudinal axis of the bottom unit.

6. A cash carrier for cable despatch systems comprising a bottom unit having a cavity therein, a bracket secured within the cavity having spaced ears supporting a pintle pin for pivotally supporting a cable gripping jaw, a bridge member connecting said ears, and a spring interposed between said bridge member and the jaw for resiliently urging the latter toward cable gripping position.

Signed by me at New York, N. Y., this 11th day of June 1923.

ARCHIBALD B. CLEMENTS.
